Primary Examiner — Thomas Johannes(74) *Attorney, Agent, or Firm* — Woodling, Krost and Rust**CLAIM**

The ornamental design for a switch, as shown and described.

DESCRIPTION

FIG. 1 is a front perspective view of the switch showing my new design;

FIG. 2 is a right side view thereof;

FIG. 3 is a left side view thereof;

FIG. 4 is a back side view thereof;

FIG. 5 is a front side view thereof;

FIG. 6 is a top view thereof;

FIG. 7 is a bottom view thereof;

FIG. 8 is a front perspective view of a second embodiment of the switch showing my new design;

FIG. 9 is a right side view of the second embodiment;

FIG. 10 is a left side view of the second embodiment;

FIG. 11 is a back side view of the second embodiment;

FIG. 12 is a front view of the second embodiment;

FIG. 13 is a top view of the second embodiment; and,

FIG. 14 is a bottom view of the second embodiment.
